UNITED STATES PATENT OFFICE

CHAUNCEY MARSH GOODRICH, OF WINDSOR, ONTARIO, CANADA

TOWER ARM

Application filed March 20, 1929. Serial No. 348,529.

This invention relates to transmission towers and more particularly to swinging arms for said towers, and has for its object the provision of arms of this type which are free to swing in a horizontal direction parallel with the line.

Another object is to provide a tower arm of this class which will be light in weight, cheap to manufacture and of durable construction.

10 In the drawings—

Figure 1 is an elevation of a tower having the novel arm construction of this invention.

15 Figure 2 is a sectional view taken on the line II—II of Figure 1.

Figure 3 is an enlarged elevation of the upper end of the tower showing the construction of the arm and its mounting in detail.

20 Referring more particularly to the drawings, the numeral 2 designates the legs of the tower which is of the usual skeleton construction. The legs 2 are connected by bracing 3 in the usual manner.

25 A triangular head member A is provided on the upper end of the tower to support the cable carrying arm B. The head A is composed of channel sections 4 which are secured to and extend upwardly from the upper ends of the legs 2. The channel sections 4 extend 30 upwardly parallel with the legs 2 for a short distance and are then bent over toward each other in a direction parallel with the line until their upper ends meet. Connecting plates 5 are secured between the upper ends of the channel members 4 and an angle tie bar 6 is secured to said plates. Mounting plates 7 are 35 secured to the channels 4 on the sides whose planes are parallel with the line.

40 Hanger bars 8 are pivotally connected to the plates 7 by bolts 9 and depend therefrom so as to swing in a direction parallel with the line.

45 A horizontal cable supporting beam 10, composed of a pair of angles secured together back to back, is secured to the lower ends of the hanger bars 8 and extends through the tower head A and beyond each side thereof. Suitable bracing bars 12 extend from adjacent the upper end of the hanger bars 8 to adjacent the outer ends of the beam 10. The

hangers 8, beam 10 and bracing bars 12 form the cable carrying arm B which is free to swing in the direction of the line.

Suitable stop and guide lugs 14 are secured to the under face of the beam 10 slightly beyond the sides of the tower and are adapted to engage tower horizontal bracing members 15 to limit and prevent the swinging of the arm B transversely of the line and to guide the arm during its swinging movement in the direction of the line.

Suitable insulator hangers 16 are suspended from the arm B at points adjacent each end of the beam 10 to support the transmission line cables. Other insulator hangers 17 may be suspended from each of the plates 5 and have their lower ends connected together to form a central support within the tower head A for another cable if desired.

By providing the swinging arm B, if undue load is applied to one side of the arm due to ice or snow collecting on the cable, the arm is free to swing and reduce the strain on the cables. If one or both of the cables break, the arm will also swing so as to reduce the strain on the unbroken cables.

While I have shown and described one specific embodiment of my invention it will be understood that I do not wish to be limited thereto, since various modifications may be made without departing from the scope of my invention, as defined in the appended claims.

I claim—

1. The combination with a transmission tower, of an arm construction comprising a beam member extending through the tower and beyond each side thereof in a direction transverse to the line, a pair of spaced hanger bars hingedly connected to said tower and connected to said beam to form a floating support for said beam so that said beam is free to swing horizontally in a direction parallel with the line, and means for preventing the swinging of said beam in a direction transverse of the line.

2. The combination with a transmission tower, of an arm construction comprising a beam member extending through the tower and beyond each side thereof in a direction

- transverse to the line, a pair of spaced hanger bars hingedly connected to said tower and connected to said beam to form a floating support for said beam so that said beam is free to swing horizontally in a direction parallel with the line, diagonal truss bars extending from adjacent the free ends of said beam to said hangers, and means for preventing the swinging of said beam in a direction transverse of the line.
3. The combination with a transmission tower, of an arm construction comprising a rigid beam member composed of a pair of angles secured together back to back, said beam extending through the tower and beyond each side thereof in a direction transverse to the line, a pair of spaced hanger bars hingedly connected to said tower and connected to said beam to form a floating support for said beam so that said beam is free to swing horizontally in a direction parallel with the line, diagonal truss bars extending from adjacent the free ends of said beam to said hangers, and means for preventing the swinging of said beam in a direction transverse of the line.
4. The combination with a transmission tower, of an arm construction comprising a beam member extending through the tower and beyond each side thereof in a direction transverse to the line, a pair of spaced hanger bars hingedly connected to said tower and connected to said beam to form a floating support for said beam so that said beam is free to swing horizontally in a direction parallel with the line, stop lugs on said beam and adapted to engage said tower to guide said beam and prevent the swinging of said beam in a direction transverse of the line.
- 40 In testimony whereof, I have hereunto set my hand.

CHAUNCEY MARSH GOODRICH.
